(57) CLAIM

We claim the ornamental design for a bolt on grille badge, as shown and described.

DESCRIPTION

FIG. 1 is a perspective view of a bolt on grille badge according to our invention.

FIG. 2 is a top view of the bolt on grille badge.

FIG. 3 is a front view of the bolt on grille badge.

FIG. 4 is a bottom view of the bolt on grille badge.

FIG. 5 is a rear view of the bolt on grille badge.

FIG. 6 is a left side view of the bolt on grille badge; and, FIG. 7 is a right side view of the bolt on grille badge.

The bolt on grille badge of the invention is characterized by vertical intersecting radii that resemble “Hearts”.

The broken line showing of environment is for illustrative purposes only and forms no part of the claimed design.
